DESIGN FOR A DRESS

Jack Wasserman, Lawrence, N. Y.

Application November 24, 1939, Serial No. 88,437

Term of patent 3½ years

To all whom it may concern:

Be it known that I, Jack Wasserman, a citizen of the United States and a resident of the city of Lawrence, in the county of Nassau and State of New York, have invented a new, original, and ornamental Design for a Dress, of which the following is a specification, reference being had to the accompanying drawing, forming a part thereof:

Fig. 1 is a front view of a dress showing my new design.

Fig. 2 is a rear view of the dress shown in Fig. 1.

The characteristic feature of my design resides in the loose panel from the shoulder to the waist portion which is gathered and held in draped position by bows and a wide plain waist band in inverted V-shape, the bottom of said waist portion being trimmed with pleating in association with the sleeves and skirt as shown.

I claim:

The ornamental design for a dress, substantially as shown and described.

JACK WASSERMAN.
